[57] **CLAIM**

The ornamental design for a package for safety razors, as shown and described.

DESCRIPTION

FIG. 1 is a front perspective of a package for safety razors showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a plan view thereof, shown in an unassembled condition.

The broken line showing of safety razors is for illustrative purposes only and forms no part of the claim.

FIG. 1

FIG. 2

FIG. 3

FIG. 4

FIG. 5

FIG. 6

FIG. 7

FIG. 8
